DAVID CUMMING, OF PHILADELPHIA, PENNSYLVANIA.

Letters Patent No. 86,894, dated February 9, 1869.

IMPROVED ICE-CREEPER.

The Schedule referred to in these Letters Patent and making part of the same.

To all whom it may concern:

Be it known that I, DAVID CUMMING, of Philadelphia, Pennsylvania, have invented an Improved Creeper; and I do hereby declare the following to be a full, clear, and exact description of the same.

My invention consists of a creeper, constructed in the peculiar maner fully described hereafter, for ready and firm attachment to, and as ready displacement from the sole of a boot or shoe.

In order to enable others to make and use my invention, I will now proceed to describe the mode of constructing and applying the same, reference being had to the accompanying drawing, which forms a part of this specification, and in which—

Figure 1 is a sectional view of my improved creeper, attached to the sole of a boot;

Figure 2, a perspective view;

Figure 3, an inverted plan view; and

Figure 4, a sectional view, showing the creeper detached from the boot.

Similar letters refer to similar parts throughout the several views.

A and A' are two plates, connected together by a strip, B, of rubber or elastic fabric.

The under side of the portion a of each plate is roughened, and between the rough surface and a metal strip, b, (the latter being also roughened,) is secured the elastic strip B, by rivets, the heads of which are so pointed as to form the spikes of the creeper.

The metal strips b are of such a length that the strip of one plate shall underlap that of the other plate when the creeper is adjusted to the boot, as shown in fig. 1.

On the upper edge of the portion e of each plate are two projections, f f, those of one plate for fitting over

one edge of the sole, and those of the other plate for fitting over the opposite edge of the sole.

In adjusting the creeper to its place, the lips f f of one of the plates are hooked over one edge of the sole, and then the other plate, after stretching the elastic strip, is adjusted with its lips to overlap the opposite edge of the sole.

On placing the foot on the ground, and bearing with the weight of the body on the creeper, the projections on the portions a of the plates will penetrate the sole of the boot, and thus prevent all tendency of the creeper to slip longitudinally, while the tendency of the stretched strip B to recoil causes the creeper to maintain its hold of the sole laterally with a sufficiently firm gripe to prevent displacement.

The metal strips b, while serving to aid in securing the elastic strip, protect the latter from being unduly worn or injured by rough roads.

The creeper, as will be evident, can be readily detached when necessary, and folded in a small compass.

I claim as my invention, and desire to secure by Letters Patent—

1. Spiked plates A and A', adapted to the edge of the sole, and connected together by an elastic strip, all substantially as and for the purpose herein set forth.

2. The metal strips b, connected to the plates A A', and overlapping below the rubber strip B, as specified.

In testimony whereof, I have signed my name to this specification, in the presence of two subscribing witnesses.
